UNITED STATES PATENT OFFICE.

ELI T. STARR, OF PHILADELPHIA, PENNSYLVANIA, ASSIGNOR TO THE
S. S. WHITE DENTAL MANUFACTURING COMPANY, OF SAME PLACE.

DESIGN FOR A GUM FOR ARTIFICIAL TEETH.

SPECIFICATION forming part of Design No. 19,362, dated October 15, 1889.

Application filed April 16, 1884. Serial No. 128,160. Term of patent 14 years.

To all whom it may concern:

Be it known that I, ELI T. STARR, of the city and county of Philadelphia, in the State of Pennsylvania, have invented and produced a new Design for the Gums of Artificial Teeth, of which the following is a specification, reference being had to the accompanying drawings, in which—

Figure 1 is a front view of the artificial gum for a complete upper and lower set of teeth, the appropriate teeth being shown as set opposite each other; and Figs. 2 and 3 are sections therethrough on the lines 2 2 and 3 3, respectively.

My design consists in the gum of an artificial denture having a corrugated or raised and depressed appearance upon the labial surface thereof, with a swell or ridge along the border or margin of the gum next the necks of the teeth, in contradistinction to the gum of an artificial denture having a comparatively-smooth convex labial surface without such marginal swell, as heretofore.

A specific description of the appearance of one section or block of gum-teeth will suffice for a full disclosure of the design.

Referring to the several figures of the drawings, and taking, for instance, section A of Fig. 1, it will be seen that the gum is raised, as at *a a a*, over the roots of the teeth and above the necks thereof, and has a well-defined swell along its border or margin over the necks of the teeth, while between the roots or hidden portions of the teeth the gum is depressed, as at *b b*, whereby the gum has the corrugated appearance desired, with the line of demarkation between the teeth and gum well defined.

The design is clearly illustrated by the drawings, and is of course applicable to gums for single teeth as well as to blocks or sections thereof.

I claim—

The artificial gum of gum-teeth, having the corrugated appearance and the marginal swell, substantially as shown and described.

In testimony whereof I have hereunto subscribed my name.

ELI T. STARR.
